FLAME CONTROL FOR BURNERS OF THE
SOLIDIFIED NORMALLY LIQUID FUEL
BURNING TYPEAlbert Joseph Laliberte, West Cheshire, Conn.,
assignor to Safety-Fuel Incorporated, West
Cheshire, Conn., a corporation of Connecticut

Application October 15, 1946, Serial No. 703,315

7 Claims. (Cl. 158—97)

1

This invention relates to new and useful improvements in flame control for burners of the solidified normally liquid fuel burning type.

Burners of this type are designed for use with a solidified normally liquid fuel, such as a suitably solidified kerosene or other flammable petroleum hydrocarbon. In these burners the solidified fuel is vaporized by part of the heat of the burner and the fuel vapors are passed into a combustion chamber where they are suitably mixed with air and combusted. Though frequent attempts have been hitherto made to control the rate of flow of vaporized fuel into the combustion chamber and thereby control the flame of the burner, none have been satisfactory. Yet such flame control is highly desirable not only for controlling the burner output as between high and low flame and various intermediate positions, but also with respect to its complete and safe extinguishing, at any time. Though the burner flame can be always extinguished, the lack of a satisfactory control will cause fuel vapors to continue to emanate from the fuel receptacle by reason of the heat within the fuel receptacle or continue to be absorbed by the same for an appreciable period of time after extinguishing the flame. This may cause dangerous conditions and fire hazards as the vapors remain unchecked and will leak to the outside.

One object of the instant invention is to provide a flame control for burners of the solidified normally liquid fuel burning type.

This and further objects thereof will appear from the following description read in conjunction with the drawings in which:

Fig. 1 is a perspective view of a burner construction in accordance with the invention;

Fig. 2 represents a cross-sectional side view of the construction shown in Fig. 1;

Fig. 3 is a top view of part of the construction shown in Fig. 2 and illustrating the burner assembly;

Fig. 4 is a cross-sectional top view of the construction shown in Fig. 2 at right angles thereto, taken in the plane II—II;

Figs. 5 and 6 illustrate respectively end and side views of a manual control in conjunction with the flame control shutter in accordance with the invention, and

Figs. 7 and 8 illustrate an alternative manual control for the operation and adjustment of the novel flame control shutter.

Referring to the drawings, 1 indicates the burner housing having a top 2, rear portion 3 and base portion 4. A door 5 is carried at the front of the

2

burner being hinged at 6 in the lugs 7 carried by the front portion 8 of the burner housing. A plate 9 is carried by the front portion 8 of the housing and serves to mount the manual operating control assembly comprising knob 10 mounted on shaft 11 extending through aperture 12 in plate 9 and carrying the camming cup 13. Support 14 is provided as a securing guide for the control assembly and further to strengthen plate 9. Door 5 carries an extension 15 serving as a door handle. The control assembly is mounted in substantially fixed position with respect to the housing and the cut-out 16 in door 5, permits the opening of the door while leaving the control assembly in position.

The burner assembly comprises two substantially concentrically arranged, substantially cylindrical members 17 and 18, provided with perforations 19 and 20 respectively. The cylindrical members 17 and 18 define therebetween the combustion space 21. Inner cylindrical member 18 carries ring cap 22. Air ducts 23 admit air to the inner cylinder. A substantially annular shield 24 carrying ring member 25 concentrically surrounds cylindrical members 17 and 18 and acts to protect the outside of the burner from excessive heat radiation and the burner itself against incipient drafts. Burner shield 24 is inserted through and held in position in the circular opening 26 in the top portion 2 of the burner housing 1. The cylindrical burner member 18 carries bottom closure 27. The back portion 3 of the burner housing 1 is preferably bolted in position, and air openings, to freely admit air for combustion, are provided at 28 in the lower part of the housing 30 rear portion 3 and at 29 in the lower part of the door 5. Support 30 secured to base portion 4 of the burner housing acts as a means of mounting the complete burner assembly. Support 30 carries burner assembly base 31 and fuel cup spring plate 32 hinged to support 30 at 33. Spring plate 32 carries handle 34 secured by screw 35 and serves to carry fuel cup 36, pressing the same under spring tension with its rim or lip 37 against the end face of the burner assembly base 31. The fuel cup 36 is provided with a handle portion 38 and knob 39. Spring plate 32 carries annular depression 40 generally conforming to the contours of the bottom of the fuel cup and serving to substantially secure and maintain the fuel cup in predetermined position in relation to the annular opening 41 within burner assembly base 31.

Shutter housing plate 42 is mounted on burner assembly base 31 in spaced relation thereto by means of the flanged or bent portion 43. Shutter

housing plate 42 carries mounted thereon the outer burner cylinder 17, by means of the flanged portions 44. Shutter housing plate 42 is provided with a substantially circular cut-out 45 and the construction is so arranged and assembled that cut-out 41 in burner assembly base 31, and cut-out 45 in shutter housing plate 42, are in substantial alignment with each other and with their outer periphery substantially aligned with the outer wall of the cylindrical burner member 17.

A shutter 46 is carried within the shutter housing 47 defined by shutter housing plate 42, its flanged or bent portion 43 and the burner assembly base 31. Cut-outs 41 and 45 in burner assembly base 31 and shutter housing plate 42 respectively define, together with the shutter housing 47, a conduit for the passage of vaporized fuel from the fuel cup 36 to the combustion space 21 defined by cylindrical burner members 17 and 18. The shutter 46 acts as a variable and adjustable closure to control the fuel vapor passage through the conduit from fully closed to fully open and intermediate positions.

Specifically referring to Figs. 4, 5 and 6, the shutter 46 comprises two members or panels 46a and 46b having facing each other mating surfaces 48a and 48b respectively. The shutter panels are pivotably hinged at 49a and 49b respectively and carry lever extensions 50a and 50b. Lever extensions 50a and 50b carry adjacent their ends apertures 60a and 60b respectively and secured therein guide members 61a and 61b. The shutter panels are movable in the fuel vapor conduit from a mating surface abutment position, substantially fully closing the conduit to the passage of fuel vapors therethrough, to a maximum spread-apart position substantially opening said conduit to the substantially unrestricted passage of fuel vapors therethrough.

Specifically referring to Figs. 5 and 6, the cup member 13 carries camming slots or grooves 62a and 62b respectively. These slots are so arranged on the inner periphery of cup 13 that they describe or define a portion of a spiral of progressively decreasing distance from the axis of the cup. In the arrangement illustrated, turning of the cup 13 by means of the knob 10 in the direction of the arrow will result in bringing the guide members 61a and 61b closer to the axis of the cup, thus drawing them into closer proximity to each other and thereby moving the shutter portions 46a and 46b into increasingly spread-apart positions by way of their respective pivots 49a and 49b. Turning in the other direction will achieve the opposite result, i. e., the guide members or studs 61a and 61b will be moved apart with respect to each other and the shutter portions will become progressively closed. In the arrangement illustrated the camming grooves or slots are so arranged that a 180 degree turn of knob 10 will move the shutters between a completely closed and a fully opened position and any intermediate degree turn will move the shutters to any desired intermediate predetermined position of relative closure.

In lieu of the cup construction illustrated in Figs. 2-6, a substantially flat disc with camming slots or grooves may be used. Such arrangement is, for instance, illustrated in Figs. 7 and 8. As there shown, disc 70 carries spirally arranged camming grooves or slots 71a and 71b respectively. Shutter extensions 49a and 49b carry guide lugs 72a and 72b respectively. These guide lugs are in engagement with the camming slots or grooves and a turning of the disc, which

is rotatably mounted at 73, will move the extensions 49a and 49b towards each other, thus effecting a spreading of the shutter portions, and thereby causing the same to open. A 180 degree turn of the disc will cause the opening of the shutter from the fully closed to the fully opened position. Reversing the rotation of the disc, the shutter can be closed by the same 180 degree turn in the other direction. Any intermediate shutter positions may be obtained by intermediate degree turning of the disc. This construction has the advantage of ease of assembly and fewer elements. The disc is made to project beyond the burner housing for easy access.

In all cases where camming arrangements are used, it is possible to so calculate the same, if desired, that magnification of control in the "low flame" area is obtained. As illustrated in Fig. 8, this is achieved by the relatively small divergence from a cylindrical path of the closing end portions of the camming slots or grooves in contrast with the much steeper divergence from such path at the other fully open end, at which sensitive control is not required to the extent necessary under "low flame" conditions.

In the practical operation of the burner, door 5 is opened, and fuel cup 36, charged with a normally liquid solidified fuel, is inserted by lowering spring plate 32 by means of handle 34 and positioning the cup through the action of the spring plate and the depression 40. The cup fits substantially in vapor-tight closure against the burner assembly base 31. The knob 10 is turned to the left, facing the burner door, to the fully opened position. The fuel in the fuel cup is ignited and the fuel vapors emanating from the fuel pass into the combustion space 21 and are there intermixed with air entering through the perforations 23 of the inner cylinder 18 and the perforations 19 of the outer cylinder 17. Once the combustion is well under way, the volume of the fuel passing from the fuel receptacle into the combustion space can be regulated to any desired extent, thus effecting control of the burner flame by any adjustment of the shutter to any position of relative closure.

The shutter housing is so arranged and proportioned that the shutter is movable therein with a sliding substantially vapor-tight fit. Normally a fit of from $\frac{1}{1000}$ to $\frac{2}{1000}$ of an inch between shutter surfaces and inner surfaces of the housing with which the shutter is in frictional engaging contact will produce a satisfactory vapor-tight seal or fit. The housing itself should be substantially vapor-tight at the periphery thereof. This may be accomplished as, for instance, illustrated in the drawings by spot welding the flanged or bent portion of the upper shutter housing plate onto the bottom plate.

When the shutter is in the closed position it acts as a relatively closely fitting lid over the cut-out 41 of the burner assembly base 31, completely blocking the passage of fuel vapors from the fuel cup into the combustion space of the burner. The fit is sufficient to exclude the passage or leakage of vapors even under the pressure generated by the continued emanation of fuel vapors from the fuel as the result of the heat present within the fuel cup or continued to be conducted into the fuel cup for some time after the shutter is closed and the burner flame has become extinguished.

A practical test for ascertaining whether the desired vapor-tight fit is present is the holding of an open flame near all joints, as leakage will

be immediately apparent by ignition of escaping fuel fumes. Wherever, therefore, the expression "vapor-tight" or a similar term is used herein in connection with the shutter housing and/or shutter, it is intended to connote such condition or conditions as will assure the blocking of the passage of fuel vapors to the exterior of the structure in amounts that could be ignited by an open flame.

As illustrated in the drawings, the shutter housing is so arranged that it provides an opening on one side thereof through which the extensions of the shutter portions pass to the outside of the housing. The shutter extensions are preferably so arranged that they substantially fill this space, leaving only sufficient clearance on each side facing the edges of the shutter housing opening to permit the operation of the shutters and their extensions over the pivots. The inner faces of the shutter portions constitute mating surfaces which close substantially vapor-tight.

In the preferred embodiment of the invention the shutter extensions are angled with respect to the axis of the shutter halves and have rounded abutting inner faces, each in continuation and extension of its mating shutter face. This is, for instance, indicated at 80 (Fig. 4). The shutter is there illustrated in open position with the closed position indicated in dotted outline. It will be seen that the rounded surfaces at 80 constituting part of a true circle around the respective pivot points 49a and 49b will remain in abutment throughout the movement of the shutter halves between fully closed and fully opened position. In this manner a relatively tight vapor seal is established.

When the shutter is opened, even if only to a relatively small extent, fuel vapors pass through the conduit created by the opening and into the combustion space. The position of the shutter when partly opened is such that a relatively large space exists within the shutter housing in back of the shutter portions. In view of the fact, however, that there is a direct open passage to the combustion space, somewhat of a draft effect is created, causing the fuel vapors to preferentially pass into the combustion space. The fuel vapors will not pass through the back space behind the shutter portions and out through the relatively narrow space between the sides of the shutter extensions and the adjacent parts of the shutter housing opening. The relative narrowness of available space between shutter extension and adjacent rim of the opening in the shutter housing creates also a back pressure factor which aids in blocking leakage of fuel vapors through the opening of the shutter housing carrying the shutter extensions. For the same reasons the fit between the interior faces of the shutter or shutter extensions or other means providing a vapor seal at the inside of the shutter portions permits of considerable tolerance before fuel vapor leakage occurs at this point.

Thus the invention essentially embraces in a burner of the solidified normally liquid fuel burning type having a fuel receptacle and means defining a combustion space, the improvement in flame control for such burner which comprises means defining a conduit positioned and adapted to feed vaporized fuel from said receptacle to said combustion space, means defining a shutter within said conduit for substantially opening and closing said conduit to the passage of fuel vapors therethrough and means for manually adjusting said shutter to variable positions throughout its

operating range from fully closed to fully opened.

The foregoing description is for purposes of illustration and not of limitation and it is therefore my invention that the invention be limited only by the appended claims or their equivalents wherein I have endeavored to claim broadly all patentable novelty.

I claim:

1. In a burner of the normally liquid solidified fuel burning type having a fuel receptacle and means defining a combustion space, the improvement in flame control structure which comprises means defining a substantially vapor tight conduit positioned to feed vaporized fuel from said receptacle to said combustion space, means defining a shutter substantially vapor tightly arranged within said conduit for substantially opening and closing said conduit to the passage of fuel vapors therethrough, and means for manually adjusting said shutter to various positions throughout its operating range from fully closed to full opened, said receptacle and said conduit forming an air excluding substantially vapor tight unit.

2. In a burner of the normally liquid solidified fuel burning type having a fuel receptacle and means defining a combustion space, the improvement in flame control structure which comprises means defining a substantially vapor tight conduit positioned to feed vaporized fuel from said receptacle to said combustion space, means defining a shutter substantially vapor tightly arranged within said conduit for substantially opening and closing said conduit to the passage of fuel vapors therethrough, said shutter comprising two panels having substantially mating surfaces facing each other and movable in said conduit from a mating surfaces abutment position, substantially closing said conduit to the passage of fuel vapors therethrough, to a maximum spread-apart position, opening said conduit to the substantially unrestricted passage of fuel vapors therethrough, and means for manually adjusting said shutter panels to various positions throughout their range of movement, said receptacle and said conduit forming an air excluding substantially vapor tight unit.

3. In a burner construction, the improvement in accordance with claim 2 in which there are additionally provided means defining at least one substantially fuel vapor-tight housing to receive at least part of said panels when in said maximum spread-apart position.

4. In a burner of the normally liquid solidified fuel burning type having a fuel receptacle and means defining a combustion space, the improvement in flame control structure which comprises means defining a substantially vapor tight conduit positioned to feed vaporized fuel from said receptacle to said combustion space, a shutter across said conduit for opening and closing the same to the passage of fuel vapors therethrough and comprising two, substantially side by side arranged panels, having substantially mating surfaces facing each other and movable in said conduit from a mating surfaces abutment position, substantially closing said conduit to the passage of fuel vapors therethrough, to a maximum spread-apart position substantially opening said conduit to the substantially unrestricted passage of fuel vapors therethrough, a substantially fuel vapor-tight housing slidably receiving in substantially vapor-tight fit at least part of said panels when in fully spread-apart position, means defining an opening in said housing, at least one extension carried by each of said panels, said ex-

tensions extending through said opening, at least one of said panels and said extensions substantially fuel vapor tightly blocking said opening when said panels are in spread-apart position, and manually controllable means connected to said extensions for adjusting said shutter panels to various positions throughout their range of movement, said receptacle and said conduit forming an air excluding substantially vapor tight unit.

5. In a burner construction the improvement in accordance with claim 4 in which said shutter panels are pivotably mounted and in which said extensions are positioned at an angle relative to each other when said panels are in the closed position so as to close said shutters by moving said extensions away from each other and to open said shutter by moving said extensions toward each other.

6. In a burner of the normally liquid solidified fuel burning type having a fuel receptacle and means defining a combustion space, the improvement in flame control structure which comprises means defining a substantially vapor tight conduit positioned to feed vaporized fuel from said receptacle to said combustion space, a shutter across said conduit for opening and closing the same to the passage of fuel vapors therethrough said shutter comprising two, substantially side by side arranged, and substantially congruously positioned panels having substantially mating surfaces facing each other and each mounted on pivot means for pivotable movement in said conduit from a mating surfaces abutment position substantially fully closing said conduit to the passage of fuel vapors therethrough, to a maximum spread-apart position, substantially opening said conduit to the substantially unrestricted passage of fuel vapors therethrough, each of said mating surfaces terminating in a substantially circular section around its pivot means, said circular sections being arranged in engaging contact to ride upon each other in substantially vapor-tight fit throughout the range of pivot of said panels about said pivot means, a substantially fuel vapor-tight housing slidably receiving in substantially vapor-tight fit at least part of said panels when in fully spread-apart position, means defining an opening in said housing, at least one extension carried by each of said panels and extending beyond said pivot means through said opening, at least one of said extensions and said panels substantially fuel vapor tightly blocking said opening when said panels are in spaced-apart position and manually controllable means connected to said extensions for variably adjusting the angular distance therebetween throughout the range of pivot of said panels, said receptacle and said conduit forming an air excluding substantially vapor tight unit.

7. In a burner of the normally liquid solidified fuel burning type having a fuel receptacle and

means defining a combustion space, the improvement in flame control structure which comprises a substantially vapor-tight shutter housing substantially vapor-tightly positioned intermediate said fuel receptacle and said combustion space and having a top opening in direct substantially vapor tight fuel vapor feed communication with said combustion space and a bottom opening in direct substantially vapor tight fuel vapor feed communication with said fuel receptacle, a shutter within said housing comprising two panels having inner mating surfaces facing each other and each mounted on pivot means for pivotable movement in vapor-tight sliding fit with said housing from a mating surface abutment position, fully closing at least one of said openings, to a maximum spread-apart position, leaving uncovered both said openings for the substantially unrestricted passage of fuel vapors therethrough, each of said mating surfaces terminating in a substantially circular section around its pivot means, said circular sections being positioned to ride upon each other in substantially vapor-tight fit throughout the range of pivot of said panels about said pivot means, means defining an opening in said housing, at least one extension carried by each of said panels and extending beyond said pivot means through said opening, at least one of said extensions and said panels substantially fuel vapor tightly blocking said opening when said panels are in spaced-apart position, and manually controllable means connected to said extensions for variably adjusting the angular distance therebetween throughout the range of pivot of said panels, said receptacle and said conduit forming an air excluding substantially vapor tight unit.
